DESIGN FOR A RATTLE HANDLE

Paul E. Allen, Skokie, Ill.

Application October 11, 1944, Serial No. 115,702

Term of patent 14 years

(Cl. D34—15)

To all whom it may concern:

Be it known that I, Paul E. Allen, a citizen of the United States, residing at Skokie, in the county of Cook and State of Illinois, have invented a new, original, and ornamental Design for a Rattle Handle, of which the following is a specification, reference being had to the accompanying drawing, forming a part thereof.

In the drawing:

Figure 1 is a front view of a rattle handle, embodying my new design;

Figure 2 is a side elevational view thereof;

Figure 3 is a top plan view thereof; and

Figure 4 is a bottom plan view thereof.

I claim:

The ornamental design for a rattle handle, substantially as shown.

PAUL E. ALLEN.
